Patented Aug. 20, 1912.

UNITED STATES PATENT OFFICE.

SOLOMON ANDRÉ GIROUARD, OF SPENCER, MASSACHUSETTS.

SANITARY SEAT.

1,036,217.

Specification of Letters Patent. Patented Aug. 20, 1912.

Application filed July 6, 1910, Serial No. 570,547. Renewed January 17, 1912. Serial No. 671,566.

To all whom it may concern:

Be it known that I, SOLOMON A. GIROUARD, a citizen of the United States, and a resident of Spencer, in the county of Worcester and State of Massachusetts, have invented a new and Improved Sanitary Seat, of which the following is a full, clear, and exact description.

An object of the invention is to provide a foldable sanitary seat for removable attachment to water closets, to prevent the spreading of any infectious germs on the closet, to the person using the same. For the purpose mentioned use is made of a foldable casing, a pliable seat contained therein, and means for removably securing the casing to a closet, and the said seat being adapted to be withdrawn from the casing and returned thereto.

Reference is to be had to the accompanying drawings, constituting a part of this specification, in which similar characters of reference denote corresponding parts in all the views, and in which—

Figure 1 is a perspective view of a closet with my device attached thereto and in operative position; Fig. 2 is a plan view of my invention, showing the same in open position with parts broken away to disclose the underlying structure; Fig. 3 is a sectional view taken on the line 3—3 in Fig. 2; Fig. 4 is a perspective view of my device in folded position; Fig. 5 is a sectional end view showing the means for returning the seat within the casing, and taken on the line 5—5 in Fig. 8; Fig. 6 is an end view taken on the line 6—6 in Fig. 8 and looking in the direction of the arrow; Fig. 7 is a sectional view taken on the line 7—7 in Fig. 4; and Fig. 8 is a fragmentary longitudinal section, showing the position of the various operative parts when the casing is folded.

Referring more particularly to the various views, a casing 10 is provided consisting of parts 11 and 12, hinged to fold at 13. A shaft 15 is mounted to turn in the casing 10 and consists of hinged parts 16 and 17, and secured to the shaft 15 is a pliable seat 15^a. A rod 18 connects the shaft 15 with one end of the casing, the said rod being mounted to turn in a bearing 19 intermediate the end 20 and a partition 21 of the casing. The end 20 is preferably provided with an opening or slot 22, and the bearing 19 and partition 21 are similarly provided with slots 23 and 24, so that when the part 11 is folded on the part 12, the part 11 will fit

snugly owing to the slots in the partition, the end and the bearing being adapted to receive the shaft 15, as will be easily seen in Fig. 6. A partition 25 constitutes a chamber 26 at one end of the casing 10, and contained therein is a spring 27 secured to the shaft 15. The shaft 15 has secured thereto a ratchet 28 adapted to be engaged by a pawl 29 actuated by a spring 30 and controlled by push knob 31. On the casing 10 similar slotted casings 32 are provided, having therein compression springs 33, having one end thereof secured to an end of the casing and the other end thereof secured to a grip 34. When it is desired to secure the casing 10 to a closet, the grips 34 are distended and disposed to secure the closet cover therebetween, the compression of the springs 33 being sufficient to substantially secure the casing.

Assuming that the casing is in folded and closed position and it is desired to use the seat 15^a, a handle 35 on the seat 15 is grasped and the seat is drawn from the casing, in a manner similar to the unwinding of a window shade except that the material constituting the seat is folded, one half over the other, as will be seen in Fig. 4. As the seat is drawn from the casing, the pawl and ratchet mechanism described coöperate to prevent the seat from returning to the casing when the same is released, and at the same time the spring 27 is being wound. After the said seat 15^a has been withdrawn from the casing, the said casing is opened, that is, the part 11 is unfolded from the part 12, and as will be readily understood the seat will then appear in open position and as conveniently shown in Fig. 1. The casing 10 is now attached to the cover of the closet, and the seat fitted to the closet as shown in Fig. 1 is in position for use. When it is desired to retire the seat within the casing 10, the parts 11 and 12 are first folded one upon the other and the seat is folded to correspond therewith. As the parts 11 and 12 are folded together the end 20 engages the shaft 15 as shown in Fig. 8, so that when the shaft is turned the rod 18 will also turn, thus winding the seat uniformly and evenly within the casing. To retire the seat within the casing, the push knob 31 is pressed, and the pawl 29 disengaged from the ratchet 28, releases the wound spring 27, which uncoils and thus winds the seat 15^a around the shaft 15 until

the seat is entirely within the casing, with but the handle 35 projecting therefrom and as will be easily seen in Fig. 7. In this manner a convenient folding sanitary seat 5 is provided adaptable to fit any closet and insuring absolute sanitary contact with the closet.

Although for the purpose of describing my invention I have shown a particular 10 construction thereof, it will be understood that the scope of my invention is defined in the appended claims.

Having thus described my invention, what 15 I claim as new and desire to secure by Letters Patent is:

1. In a device of the class described, the combination of a seat, a casing therefor made up of a plurality of parts pivoted together whereby said parts may be extended 20 in the same plane or may overlie each other, and means carried by each of the said parts, whereby the said seat may be folded within the said parts.

2. In a device of the class described, the 25 combination of a seat, a casing therefor made up of a plurality of parts pivoted together, whereby said parts may be extended in the same plane or may overlie each other, means carried by each of the said parts 30 whereby the said seat may be folded within the said parts, and resilient means for attaching the said casing to a closet.

3. In a device of the class described, the 35 combination of a seat, a casing therefor, a plurality of parts provided with hinges whereby said parts may be extended in the same plane or may overlie each other, a

roller member carried by each of the said parts and in engagement with the said seat, whereby the said seat may be folded within 40 the said parts, and means for attaching the said parts to a closet.

4. In a device of the class described, the combination of a seat, a casing therefor, a plurality of parts provided with hinges 45 whereby the said parts may be extended in the same plane or may overlie each other, a roller member carried by each of the said parts and in engagement with the said seat, whereby the said seat may be folded within 50 the said parts, each of the said parts being provided with movable gripping means whereby the said device is adapted to be attached to a closet.

5. In a device of the class described, the 55 combination of a seat, a plurality of parts provided with hinged means at adjacent ends thereof whereby the said parts may be extended in the same plane or may overlie each other, a roller member carried by 60 each of the said parts and in engagement with the said seat, means carried by one of the said parts for actuating the said roller whereby the seat may be wound thereon, together with other means for holding the 65 said operating means in inoperative position when the said seat is withdrawn for use.

In testimony whereof I have signed my name to this specification in the presence of two subscribing witnesses.

SOLOMON ANDRÉ GIROUARD.
